UNITED STATES PATENT OFFICE.

WILLIAM PINCH, OF CLEVELAND, OHIO.

DESIGN FOR A SCENE FOR PHOTOGRAPHIC FOREGROUNDS.

41,844.

Specification for Design.

Patented Oct. 17, 1911.

Application filed May 20, 1911. Serial No. 628,563. Term of patent 3½ years.

To all whom it may concern:

Be it known that I, WILLIAM PINCH, a citizen of the United States of America, residing at Cleveland, in the county of Cuyahoga and State of Ohio, have invented a new, original, and ornamental Design for Scenes for Photographic Foregrounds, of which the following is a specification, reference being had to the accompanying drawing, forming part thereof.

The figure is a view in elevation of a scene for a photographic foreground showing my new design.

I claim:

The ornamental design for a scene for a photographic foreground as shown.

WILLIAM PINCH.

Witnesses:

VICTOR C. LYNCH,
N. L. McDONNELL.
